Charles V. Burgess INVENTOR.

UNITED STATES PATENT OFFICE.

CHARLES V. BURGESS, OF SWAMPSOFT, MASSACHUSETTS.

BEACH-REST.

1,209,808.

Specification of Letters Patent. Patented Dec. 26, 1916.

Application filed October 9, 1914. Serial No. 865,959.

To all whom it may concern:

Be it known that I, CHARLES V. BURGESS, a citizen of the United States, resident of Swampscott, in the county of Essex and Commonwealth of Massachusetts, have invented a new and useful Improvement in Beach-Rests, of which the following is a specification.

My invention relates to new and useful improvements in beach rests and my object is to provide a frame structure to which is attached a canvas or other covering to form a rest or support for the back or body of a person leaning against the frame.

A further object is to provide suitable brace members for holding the frame in substantially vertical position. And a further object is to provide means for regulating the position of the brace members whereby the frame will be supported at different angles.

Other objects and advantages will be hereinafter set forth and more particularly pointed out in the accompanying specification.

In the accompanying drawings which are made a part of this application, Figure 1 is a perspective view of the beach rest set up for use. Fig. 2 is a perspective view of the beach rest in folded position. Fig. 3 is a detail perspective view showing the manner of clamping the brace members together. Fig. 4 is an elevation of one end of one of the brace members, and Fig. 5 is a perspective view looking from the rear portion of the beach rest.

Referring to the drawings in which similar reference numerals designate corresponding parts throughout the several views, 1 indicates the frame bars which are two in number, to the edges of which are secured in any suitable manner the edges of a strip of canvas 2, or similar material, the lower end of the canvas being extended forwardly from the frame bars to form a rug 3.

In order to hold the frame bars in elevated position when used, a pair of brace bars 4 are provided, said brace bars being in crossed relation with each other and are pivotally secured together at their point of crossing by introducing a bolt 5 through the brace bars and engaging a wing nut 6 with the extended end of the bolt.

The upper ends of the brace bars are attached to the frame bars 1 by extending cords, or the like 7 through the frame bars

1 at a point adjacent their upper ends, said cords entering channels 8 in the upper ends of the brace bars, said channels terminating at their lower ends in bores which are 60 formed through the solid portion of the brace bars and communicate at one end with one face of the brace bars and at the opposite end with the channels.

Additional cords 7' are connected to the 65 upper ends of the brace bars and are extended to the lower ends of the brace bars and through openings 9 and thence forwardly through openings 10 in the lower end of the frame bars 1, the cord engaged 70 with the upper end of one brace bar passing through the opening 9 of the opposite brace bar.

By attaching the brace bars to the frame bars through the medium of cords, as shown, 75 a more or less flexible connection will be formed between the brace bars and frame bars, and it will likewise be seen that the lower ends of the brace bars may be readily moved inwardly or outwardly to change the 80 elevation of the frame bars.

When the device is set up for use, the rug portion 3 will fully protect the garments of the person from coming in contact with the sand and soil, while the frame and canvas secured to the same will form a convenient rest or support for the upper portion 85 of the body.

When the device is not in use, the wing nut 6 may be loosened and the parts folded together into a compact bundle, as shown in Fig. 2 of the drawings, any suitable means being employed for holding the parts in folded position as by means of a hand strap 11, making the device convenient for 90 transportation.

Having thus fully described my invention what I claim as new and desire to secure by Letters Patent is:

1. A beach rest comprising a pair of frame bars, a canvas structure attached to the frame bars and terminating at its lower end in a rug portion, a pair of crossed brace bars, means to adjustably secure the brace bars together in crossed relation, the upper ends of said brace bars having channels, said brace bars having bores communicating with one end of the channels, cords attached to the frame bars and extending through said channels and bores, additional cords extending from the upper ends of the brace bars through the lower ends of the brace bars 100 105 110

- and into engagement with the lower ends of the frame bars, a cord from the upper end of one brace bar extending through the lower end of the opposed brace bar.
- 5 2. In a beach rest, the combination with a pair of frame bars, a canvas structure attached to said frame bars, said canvas structure terminating in a rug section, of a pair of crossed brace bars, flexible means for attaching the upper ends of the brace bars to the frame bars, means to adjustably secure the brace bars together in crossed relation,
- 10 cords extending from the upper ends of the brace bars through the lower ends of the brace bars and into engagement with the 15 lower ends of the frame bars, a cord from the upper end of one brace bar extending through the lower end of the opposed brace bar.

CHARLES V. BURGESS.
